Specification for Design.

Patented May 25, 1920.

Application filed January 2, 1920. Serial No. 349,071. Term of patent 14 years.

To all whom it may concern:

Be it known that I, ARTHUR A. KRAEUTER, a citizen of the United States, residing at South Orange, in the county of Essex and State of New Jersey, have invented a new, original, and ornamental Design for a Golf-Club Head, of which the following is a specification, reference being made to the accompanying drawings, forming part thereof.

In the drawings Figure 1 is a front view, Fig. 2 is a side view, looking to the right on Fig. 1, and Fig. 3 is a top view, looking down on Fig. 1, of a golf club head embodying my design.

I claim:

The ornamental design for a golf club head as shown.

ARTHUR A. KRAEUTER.
